[57] **ABSTRACT**

A device for scavenging magnetizable powder from e. g. a drum in a printing apparatus. The powder is attracted from the drum to the surface of a nonmagnetic tube positioned parallel to the drum, which has contained therein a rotatable set of adjacent bar magnets. The rotation of the magnets causes, via the bar magnets' divergent magnetic flux field, the attracted powder to work its way around the surface of the tube in opposite direction to the magnet rotation and onto a ledge extension of the tube surface. The powder eventually is moved sufficiently distant from the field to enable it to fall into a collector trough.

MAGNETIC POWDER SCAVENGING ARRANGEMENT

BACKGROUND OF THE INVENTION

This invention relates to magnetic printing and/or display devices, and in particular to magnetic powder scavenging apparatus therefor.

Such magnetic devices are well known, and essentially comprise a magnetizable surface, such as the surface of a drum or belt, which is movable relative to a set of recording heads and can be selectively magnetized by the heads in accordance with the matter to be printed or displayed, the surface then being "dusted" with magnetic powder which adheres to the magnetized regions, thus forming a powder "image." The dusted surface may then be used directly for display of the powder image, or it may be used as a printing element for transferring the image to a further surface such as a paper tape or sheet.

In copending U.S. application, Ser. No. 29,330, filed Mar. 18, 1970, we describe apparatus for dusting the magnetizable surface of a magnetic printing and/or display device. The same principle upon which that apparatus was based can be used to scavenge unwanted powder from the magnetizable surface after printing and/or display has been effected, in readiness for a fresh recording.

SUMMARY OF THE INVENTION

According to the present invention there is provided in a magnetic printing and/or display device an arrangement for scavenging magnetic powder from the movable magnetizable surface of the device, the arrangement including a nonmagnetic tube disposed adjacent the magnetizable surface, the axis of the tube being parallel to the surface and perpendicular to its direction of movement, a magnetic rotor inside the tube whose axis is parallel with the tube, the rotor producing a system of magnetic flux at the outer surface of the tube which is divergent in a plane perpendicular to the tube axis, and a nonmagnetic ledge extending substantially tangentially from the outer surface of the tube, the arrangement being such that rotation of the rotor in a given direction causes powder attracted by the rotor from the magnetizable surface to creep around the outer surface of the tube and onto the ledge by somersaulting of the powder as the divergent flux field repeatedly scans the outer surface of the tube, the powder being returned under the influence of gravity from the ledge to a container.

BRIEF DESCRIPTION OF THE DRAWINGS

An embodiment of the invention will now be described, by way of example, with reference to the accompanying drawings, in which:

FIG. 1 is a schematic representation in perspective view of the relevant parts of the magnetic powder scavenging arrangement in a magnetic printing and/or display device according to the invention; and

FIG. 2 is a cross-sectional view of the arrangement of FIG. 1.

DESCRIPTION OF THE PREFERRED EMBODIMENT

Referring to the drawings, which are not to scale, the device includes a drum 1 which is mounted in opposite walls 2 of the device housing for rotation about an axis 3. The cylindrical surface 4 of the drum is magnetizable and constitutes the surface on which matter to be printed and/or displayed is recorded as the drum rotates by a stationary set of recording heads, not shown.

A nonmagnetic tube 5, for example of aluminum, is disposed above and adjacent the drum 1 with its axis parallel to the surface 4 and perpendicular to the direction of movement of the latter. At each end, the tube 5 meets the respective wall 2 so that magnetic powder cannot enter the inside of the tube. A nonmagnetic ledge 6 extends tangentially from the outer surface of the tube 5 and curves downwardly and outwardly so that its free edge hangs clear of the drum 1.

A magnetic rotor 7 is located inside the tube 5 for rotation about an axis 8 parallel with the tube. The rotor may comprise a plurality of mutually parallel bar magnets 9, which are disposed side-by-side with their like poles adjacent, thus effectively forming a flat rectangular magnet magnetized from edge to edge in a direction perpendicular to its axis. Each edge of the rotor produces at the outer surface of the tube 5 a system of magnetic flux which is divergent in a plane perpendicular to the tube axis (FIG. 2).

In operation, the drum rotates in the direction of the arrow A, and after display and/or printing of the recorded matter has taken place in the usual way the surface 4 of the drum moves towards the tube 5. The rotor 7 rotates in the direction of arrow B and scavenges the powder 10 still adhering to the surface 4 by attraction onto the tube 5 as the surface 4 moves past the tube. The arrangement is such that the attracted powder 11, according to the principle discussed in the copending application referred to above, creeps around the outer surface of the tube 5 in the direction of arrow C, i.e. in the opposite direction to the direction of rotation of the rotor, and onto the ledge 6 as the flux system repeatedly scans the outer surface of the tube. Then under the influence of gravity the powder slides down the ledge and falls into a trough 12 below the drum. The trough 12 contains the supply of powder used for dusting the drum surface after the matter has been recorded, preferably using the powder applicator described in the copending application mentioned above, and thus the scavenged powder can be reapplied to the drum surface.

Each grain of powder is held in position on the tube by the attraction of its circumferential neighbors, but to assist somersaulting up the side of the tube it may be necessary artificially to roughen the outer surface. We have found that rubbing the outer surface with a medium grade emery paper gives a suitable surface.

It is to be understood that the foregoing description of specific examples of this invention is not to be considered as a limitation of its scope.

I claim:

1. In a magnetic printing and/or display device, an arrangement for scavenging magnetic powder from the movable magnetizable recording surface of the device, comprising a nonmagnetic tubular element relatively immovably disposed adjacent to the magnetizable surface, the axis of said tubular element being parallel to the magnetizable surface and perpendicular to the direction of movement thereof, a magnetic rotor arranged concentrically within said element, the rotor producing a system of magnetic flux at the outer surface of said nonmagnetic element which is divergent in a plane perpendicular thereto, and a nonmagnetic ledge extension to said tubular element extending substantially tangentially from the outer surface thereof, the arrangement being such that rotation of the rotor in a given direction causes powder attracted by the rotor from the magnetizable recording surface to creep in the opposite direction around the outer surface of said nonmagnetic tubular element and onto said ledge by somersaulting of the powder as the divergent flux field of the rotor repeatedly scans the outer surface of said element, the powder being returned under the influence of gravity from said ledge to a powder reservoir.

2. The arrangement according to claim 1 wherein when the magnetizable recording surface is provided by a drum, said nonmagnetic tubular element is disposed above the drum, and said nonmagnetic ledge extension curves downwardly and outwardly from said tubular element so that its free edge hangs clear of the drum.

3. The arrangement according to claim 1 wherein said magnetic rotor is a flat rectangular magnet magnetized from edge to edge in a direction perpendicular to its axis of rotation.

4. The arrangement according to claim 3 wherein the flat rectangular magnet comprises a plurality of mutually parallel bar magnets disposed side-by-side with their like poles adjacent.
